UNITED STATES PATENT OFFICE.

GUSTAV A. BADER, OF ROCHESTER, NEW YORK

EYEGLASS-MOUNTING.

1,094,512.

Specification of Letters Patent. Patented Apr. 28, 1914.

Application filed August 7, 1912. Serial No. 713,939.

To all whom it may concern:

Be it known that I, GUSTAV A. BADER, a citizen of the United States, and resident of Rochester, in the county of Monroe and State 5 of New York, have invented certain new and useful Improvements in Eyeglass-Mountings, of which the following is a specification.

This invention relates to eyeglass-mountings of the type in which the nose-guards or clamps are carried by levers, which are pivoted to the body of the mounting and controlled by finger-pieces and springs.

The principal object of the invention is 15 to produce an eyeglass-mounting of the type in question in which the springs, by which the nose-clamp levers are controlled, are so supported and mounted as to reduce the friction between these springs and their supporting-devices, while at the same time the 20 springs are securely held in place when in use and are readily removable and replaceable for the purpose of adjustment or replacement.

25 Another object of the invention is to produce a construction in which the pivotal bearings of the nose-clamp levers are so formed as to diminish the friction and wear incident to the movements of the levers.

30 To the foregoing ends I employ a construction in which the nose-clamp springs have coiled portions which are supported by members projecting in line with the pivotal axes of the nose-clamp levers, these members being freely rotatable so as to turn when 35 the levers are swung about their pivots, thus diminishing the friction between the spring-supports and the coils of the springs due to the movement of the spring-coils.

40 Other features of the invention will be set forth in connection with the following description of the illustrated embodiment thereof.

In the drawings: Figure 1 is a plan-view, 45 on a greatly enlarged scale, of a portion of an eyeglass-mounting embodying the present invention; and Fig. 2 is a rear-elevation, in section on the line 2—2 in Fig. 1.

The invention is illustrated as embodied in 50 an eyeglass mounting in which the lens-clips, by which the lens 4 is supported, the rigid yoke or bridge 5, and the body-portion 6 which connects the lens-clips and the bridge, are of ordinary form and construction. The 55 body-portion 6 has a flat upper surface upon which the nose-clamp lever 7 has a bearing

in the usual manner. The lever 7 may have any ordinary or suitable general form, and it is provided, at its rear-end, with the usual nose-clamp 8, while its forward extremity 60 constitutes a finger-piece 9 for actuating the lever.

The novel features of the present invention reside in the form and arrangement of the means for pivoting the nose-clamp levers 65 and for supporting the springs by which the nose-clamp levers are controlled. A pivot-screw 11 is threaded into each body-portion 6, and this pivot is surrounded by a bearing-sleeve 10 which is free to turn upon the 70 pivot. The upper end of the sleeve is engaged by the head of the screw, while the lower end engages the upper surface of the body 6, and to confine the sleeve against end-wise motion the screw is driven into the 75 body-portion until there is no superfluous looseness, and is then fixed in this position by upsetting the lower end of the screw as shown in Fig. 2. The nose-clamp lever does not directly engage the pivot, but is per- 80 forated to receive the lower end of the sleeve 10, and this end is reduced in diameter so as to form a shoulder, which bears upon the upper surface of the lever. The lever is thus pivoted upon the sleeve, while being free to 85 turn with respect to the latter, and the shoulder confines the lever closely against the upper surface of the body-portion 6, thus restricting the lever to pivotal movements about the axis of the pivot 11, or in a horizontal plane. The sleeve 10 constitutes the support for the nose-clamp spring. This 90 spring is provided with a helical coiled portion 12, which surrounds the sleeve, and at the upper end of the coiled portion the 95 spring terminates in a straight arm 13 which engages the rear-portion of the nose-clamp lever, as shown in Fig. 1. The lower extremity of the spring has the form of a hook 14, which passes around and under the body-portion, thus normally retaining the spring 100 against either rotation or longitudinal movement on its support.

To prevent the upper coils of the spring from becoming accidentally disengaged 105 from the upper end of the support, the sleeve 10 is provided, at its upper end, with an enlarged head or flange 15. When the spring is in use the effect of its torsion, as transmitted through the extremities 13 and 110 14, causes the spring-coils to be forced laterally into engagement with one side of the

support. By this action the uppermost coil is held beneath or interlocked with the flange 15, as shown in Fig. 2. The coiled portion of the spring is preferably made of such size, however, that when the spring is relieved of torsion by the disengagement of the arm 13 from the nose-clamp lever, the coils may be passed easily over the flange 15, so that the spring may be readily removed 10 and replaced when necessary without disassembling the mounting by the removal of the pivot-screw.

In mountings of the ordinary form, in which the spring-support is stationary, the 15 torsional action of the spring, when the nose-clamps are swung away from each other by the manipulation of the finger-pieces, causes the spring-coils to press and bind against the support, and the friction 20 thus produced results eventually in wear upon the spring and upon the support, and also interferes to some extent with the effective operation of the springs upon the levers. In the present construction, however, 25 the use of the freely-rotatable sleeve 10 eliminates, or largely diminishes, the binding of the spring, since this sleeve, when subjected to any substantial friction by the spring, will rotate with the coils of the spring. The sleeve also diminishes the friction 30 against the lever at its pivotal bearing, since it turns in the same direction as the lever, and if at any time the friction between the lever and the sleeve is greater 35 than that between the sleeve and the spring,

the sleeve will turn in unison with the lever, while, on the other hand, if the friction between the sleeve and the spring becomes greater than that between the sleeve and the lever, the sleeve will accommodate its 40 movements to those of the spring. The sleeve thus constitutes a device for automatically diminishing friction in the mechanism wherever it would otherwise be greatest, and this greatly diminishes the wear 45 upon the mechanism and distributes such wear as is not entirely eliminated in such a manner as to prevent the occurrence of substantial looseness in any part of the mechanism.

I claim:—

An eye-glass mounting having, in combination, a fixed portion comprising a body with a pivot projecting therefrom, a sleeve embracing and freely rotatable upon the pivot and having its end adjacent the body reduced in diameter so as to form a shoulder, a nose-clamp lever seated against the body and loosely embracing said reduced portion, said lever being held against the body by said shoulder, and a spring comprising a helical coiled portion surrounding said sleeve above the nose-clamp lever, and extremities engaging, respectively, the fixed portion of the mounting and the nose-clamp lever.
